ROTARY FIREPLACE

David T. Borgstrom, Los Angeles, Calif.

Application September 27, 1937, Serial No. 165,815

6 Claims. (Cl. 126—125)

This invention relates to a reversible or rotatable fireplace structure which is capable of being installed in a position wherein it fills an opening through one or more partitions in order that the fireplace may be rotationally adjusted to present its open side to any one of a plurality of rooms which are separated from each other by the partition or partitions in which the fireplace is installed.

10 An object of the invention is to utilize heat in a fireplace structure by constructing the fireplace in such a manner that while one room is being heated by radiation of heat from an open fireplace, another room would be heated by the 15 conduction of heat through a closure wall provided for one side of the fireplace.

Another object of the invention is to provide a fireplace structure which while heating one room by means of an open fireplace and heating 20 another room through a fireplace wall thus safeguards children who may be occupying the latter room from direct contact with the fire within the fireplace.

Among other objects of the invention is to 25 provide a superior mounting means for a rotatable fireplace structure; to provide superior means for conserving the heat produced in the fireplace; and to improve upon various details of fireplace construction as will hereinafter appear.

Referring to the accompanying drawing which illustrates what is at present deemed to be a preferred embodiment of the invention,

Fig. 1 is a front view of a fireplace structure as the same appears within a room which is heated by conduction of heat through the fireplace wall.

Fig. 2 is a vertical mid-section taken on line 2—2 of Fig. 1.

Fig. 3 is a transverse section on line 3—3 of Fig. 2.

Referring in detail to the drawing, the fireplace is shown installed within a building structure having a floor 10 and a partition 11, said partition being furnished with an opening 12 adjacent to the floor. Above said opening 12 there is built into the wall a conically shaped hood 13 which communicates at its upper end with a wall flue 14.

50 In the lower portion of the partition opening 12 is built a circular stationary base 15 of any suitable fireproof material. The rotatable fireplace construction is mounted upon said base and includes a circular base plate 16 which is preferably supported upon said base by means

of antifriction balls or rollers 17 which travel upon an annular track member 17a. Upon said base plate is mounted in a fixed relation thereto an angular fireplace wall structure 20 external to which is a somewhat more than semi-circular 5 plate or wall 18, said wall 18 extending up to a point substantially on the level with the lower edge of the conical hood 13. By preference and as shown the angular wall structure 20 is made to simulate a brick wall fireplace interior, while 10 the convexed wall portion 18 is suitably ornamented.

The rotary portion of the fireplace structure is completed by a frusto-conical shell 22 the lower edge of which forms an upper continuation of said curved wall 21, said frusto-conical part communicating at its upper end with a flue tube 23 which communicates with the flue 14, the outer wall portions and the top cross wall 19a. Vent openings 18a are provided to allow 20 heated air to pass through the wall 18 into the room behind the open side of the fireplace.

As shown in Fig. 2 the stationary hood 13 does not taper upwardly as rapidly as the rotatable conical member 22 and is also of a somewhat greater diameter at its lower end than the latter member. Also the inner angle of the fireplace wall portion 20 is spaced a considerable distance from the central portion of the convexed wall 18. By this arrangement a hot air chamber is provided between the walls 18 and 19 of the rotatable fireplace construction, this chamber having a lower base portion 24 and an upper portion 25. In order to add to the amount of heat conducted from the inner wall portion of the fireplace the shell 22 is provided in its lower portion and at the back side of the fireplace with an alcove 26 produced by forming a two part angular depression in the wall at this point. A restricted angular throat results between the two parts of said depression, thus producing more 40 efficient heat radiation at this point.

The stationary hood 13 is furnished with an open grill work 13a thus affording tapered openings 13b in said hood through which the hot air 45 radiates from the conical part of the fireplace freely into the rooms.

A variety of means may be used to rotate the fireplace structure manually or otherwise through a semi-circumference for the purpose of reversing the position thereof so that the open side of the fireplace may be transferred from one room to the room on the opposite side of the partition 11. In Fig. 2 of the drawing is shown the flue spout 23 having a wheel pulley 30 attached 50

externally thereto which is rotated by a belt 31 passing over a pulley 32 fixed to the shaft 33 of a motor 34. If desired a crank 35 may be added for manual rotation of the structure.

- 5 At each side of the rotatable fireplace structure a sealing member 36 may be provided, said member cooperating with the moving flanges 37 which crowd up close to the wall to make a good closure when the fireplace is turned into register with 10 either of the rooms between which the partition extends.

I claim:

1. In combination, a building structure including rooms separated by an upstanding partition 15 with an opening through it and a conical hood over said opening, said partition having a flue leading upwardly from the space occupied by said hood, and a fireplace in said opening, said fireplace having a conical top portion which communicates with said flue, said fireplace also having a fireplace opening and being turnably adjustable to direct said opening towards a selected room of aforesaid rooms.

2. In combination, a building structure including rooms separated by an upstanding partition with an opening through it and a hood over said opening, said partition having a flue leading upwardly from the space occupied by said hood, and a fireplace in said opening, said fireplace 20 having a top portion which communicates with said flue, said top portion being positioned to direct heat against the inner surface of said hood, and said hood having an open grill work to allow the heat to pass freely therethrough.

3. In combination, a building structure including rooms separated by an upstanding partition having an opening through it, a hood in said opening extending downwardly from the part of 35 said partition which is above said opening, said

hood having an opening through its top portion and said partition having a flue vertically above said opening through said hood; and a fireplace turnable in a horizontal plane and occupying said opening in said partition, said fireplace having an open lower side portion and a conical top portion furnished with an outer wall and with an inner wall in an internally spaced relation to said outer wall, thus providing a heat radiating chamber, said inner wall being furnished with a flue spout which projects upwardly into the aforementioned flue in the partition in a turnable relation thereto, and means to turn said fireplace to present its open side toward the desired side of said partition, the first recited hood 15 having openings through it to admit heat into the rooms.

4. The subject matter of claim 3 and, said flue spout of said fireplace having a wheel portion which forms a portion of said means for 20 turning the fireplace.

5. A fireplace structure positioned between adjacent rooms and including a conical top portion above a combustion space, said conical top portion having an outer heat radiating wall and a 25 wall spaced inwardly therefrom, said inner wall conducting the products of combustion upwardly from said combustion space, said inner wall having exteriorly formed in it an alcove which augments the amount of heat radiated by said 30 inner wall into the space between the outer and inner wall of said conical top portion of said fireplace.

6. The subject matter of claim 5, and, said alcove consisting of two opposed angular wall 35 depressions having an angular throat between them through which the products of combustion ascend.

DAVID T. BORGSTROM.
